UNITED STATES PATENT OFFICE

2,199,243

ELASTIC FLUID TURBINE ROTOR

George W. Mortimer, Wakefield, Mass., assignor
to General Electric Company, a corporation of
New York

Application March 1, 1939, Serial No. 259,146

5 Claims. (CL. 253—77)

The present invention relates to the construction of rotors for elastic fluid turbines of the type having a peripheral rib therein of dovetail cross-section upon which the bases of the buckets 5 are mounted and secured in place thereby. Such a construction requires modification of the shape of the rib at one or more places in its circumference to permit the buckets to be assembled in place. As a result of this, one or more spaces 10 are left between groups of buckets which must be filled with a filling block or piece to lock the buckets in place.

My invention has for its object an improved form of filling or locking piece or block for turbine rotors which is so constructed that the wedging action of the locking piece when in place is confined to certain definite selected parts of the bucket bases and is itself provided with means whereby it is securely anchored against 20 the effects of centrifugal force when the rotor is revolving at a high rate of speed.

For a consideration of what I believe to be novel and my invention, attention is directed to the accompanying description and the claims 25 appended thereto.

In the accompanying drawing which is illustrative of my invention, Fig. 1 is a perspective view of a part of a wheel showing the bucket-filling slot open; Fig. 2 is a similar view but with 30 the locking piece or block in position, and Fig. 3 is a perspective view of the locking piece or block.

In the drawing, 5 indicates a rotor for an elastic fluid turbine, such as a disk wheel for example. The wheel is provided with an annular rib 6 shaped to form the male member of a dovetail, the undercut shoulders 7 serving to hold the buckets 8 and their bases 9 against centrifugal forces. The bases are each provided with a 40 dovetail slot to receive the rib 6 and conforming in shape thereto. The rim of the wheel is also provided with small annular shoulders 10 which engage the legs or skirts 11 of the bucket bases and prevent them from spreading when the 45 buckets are subjected to centrifugal forces. The buckets are desirably integral with the bases and each has a tenon 12 to hold the bucket cover 13 in place, the tenons projecting through the cover and having their outer ends riveted over. Be- 50 cause the buckets are radially disposed, the bases thereof taper slightly toward the axis of the wheel.

In order to assemble the buckets in place, the 55 rib 6 and a part of the wheel rim have a radial slot 14 therein located in a plane perpendicular

to that of the wheel, the slot extending entirely across the rim. It is generally desirable to slot the rib and rim at two or more angularly displaced regions to facilitate assembling the buckets on the wheel and to prevent undue wear of the faces of the rib, dovetail slots in the bucket bases and other surfaces subjected to wear as the bucket bases are moved circumferentially on the rib from a filling slot to their final positions. The effect of these slots is to divide the buckets into 10 groups located on opposite sides of the slot or slots.

The bottom part of the slot 14 is in the form of a dovetail while the outer part extending through the rib is or may be parallel or slightly 15 inclined outwardly. In the slotting operation or operations, the distance between the adjacent cut ends of the rib is made slightly greater than the greatest width of the filler block 15 measured in the plane of the wheel. As a result, the bases 20 of the buckets on opposite sides of the slot extend slightly beyond or overhang the said cut ends as indicated at 16. The purpose of this is to prevent the cut ends of the rib from contacting with the filling block when the latter is forced 25 into place. The front and rear ends of the slot 14 are chamfered or cut away as at 17 to permit peening or riveting over the ends of the filler block into the cut-away portions so as to hold the same in place against endwise movement. 30 The upper edges of the dovetail part of the slot are also chamfered or beveled as indicated at 18.

The filling block 15 is best shown in Fig. 3. It is provided with a foot or dovetail 19 which snugly fits into the dovetail portion of slot 14. The 35 sides of the block as a whole from the top to the dovetail base 19 slightly taper toward the axis of the wheel in conformity with the slightly tapering bases of the buckets. It is also provided with what for convenience may be termed a head 40 20 having overhanging shoulders 21 on opposite sides. The side faces 22 thereof are the parts which engage selected portions of the adjacent bucket bases when the block is driven or forced into place under pressure. These selected portions are desirably located outside of the rib so that the filling block head cannot make contact with the cut ends of the rib. In other words, the engaging surfaces of the filling block and bucket bases are located in a region having a 45 greater diameter than the rib. The block may be drilled as indicated at 23 to lighten it when so desired. The ends of the drilled hole are desirably slightly rounded to ensure smooth surfaces. The sides of the block adjacent the dovetail base 50 55

are provided with small beveled shoulders 24 which when the block is inserted in place engage the chamfered or beveled surfaces 18 on opposite sides of the slot. The head has a slightly 5 greater width measurement in the plane of the wheel than the distance between the assembled bases of the adjacent buckets so that when the 10 block is driven or forced into place, it exerts its full wedging action or sidewise pressure on said bases and not on the cut ends of the rib, or partly on one and partly on the other which would ultimately give rise to loose buckets. Because a steam turbine wheel is subjected to greatly 15 varying temperatures which result in expansion and contraction tending to loosen the buckets, it is of paramount importance to have the bucket bases of each group firmly wedged into contact one with the other, and this is accomplished by the use of filling block of the character 20 herein described.

After the filling blocks are firmly wedged into place, the ends thereof are so peened or riveted over as to fill the chamfer 17, after which the wheel rim may be lightly machined so as to present 25 smooth side faces, as indicated in Fig. 2. After the buckets are properly assembled and anchored as above described, the cover 13 having openings registering with the tenon 12 is applied and the tenons 12 riveted over to secure the cover 30 in place.

Mention has been made of the fact that the head 20 has a greater dimension in the plane of the wheel than the portion directly under it, and this difference in dimension or clearance resulting 35 therefrom has been exaggerated in Fig. 3. The amount that these dimensions differ is usually small. In the case of relatively small diameter steam turbine wheels, the clearance on each of the opposite sides of the block below the head 40 may be of the order of a few thousandths of an inch, and the head may have a radial depth of the order of one-quarter of an inch.

An important feature of my improved construction resides in the fact that the filling block cannot be inserted in place in such manner as to make contact with the cut ends of the rib, nor can it be inserted at all if the bucket bases are not positioned as they should be. This is due to the fact that the slot 16 definitely positions the block 15, and to the further fact that the distance 45 between the cut ends of the rib is somewhat greater than the width of the head of the block. From a manufacturing standpoint, this means that faulty assembly of the block cannot be made by a careless workman. Another important feature of the construction resides in the fact that the dovetail base of the filling block securely anchors it in place and results in a simplification in the structure as a whole and a reduction in the 50 cost of manufacture.

What I claim as new and desire to secure by Letters Patent of the United States is:

1. A turbine rotor having a rim, a peripheral rib thereon of dovetail shape, the rim and rib being 55 through slotted in a plane perpendicular to the plane of the rotor to form a filling slot for buckets, the portion of the slot in the rim being of dovetail shape and that of the rib being wider than the thickness of a bucket base, buckets having 60 bases mounted on the rib and secured there-

by, and a filling block having a foot located in the slot in the rim and held by the walls thereof and also a portion located between the adjacent bucket bases and exerting sidewise pressure on selected portions thereof having a diameter greater than that of the rib. 5

2. A bucket wheel for an elastic fluid turbine having a rim, a peripheral rib thereon of dovetail shape, a slot extending through the rim and rib located in a plane perpendicular to the plane 10 of the wheel and forming a filling slot for buckets, the portion of the slot in the rim being of dovetail shape and that in the rib being of greater width than that of a bucket base and also of greater width than the filling block, and a filling 15 block having a foot anchored in the dovetail slot in the rim and a head of less width than that of the slot in the rib, the dovetail foot serving to prevent circumferential movement of the buckets on the rib. 20

3. A turbine element comprising a carrier having a rib thereon of dovetail shape in cross-section, the carrier and rib being cut through at right angles to the plane of the carrier to form a bucket assembling slot, buckets having bases 25 mounted on the rib on opposite sides of the slot, and held in position by the rib, a block located in the slot having an enlarged head, the sides of which exert a wedging action only on the bucket bases outside of the rib, the side portion of the 30 block below the head being separated by a clearance from the adjacent cut ends of the rib, and means for anchoring the block. 35

4. A turbine rotor having a rim, an annular rib thereon of dovetail shape in cross-section, the rim and rib being transversely cut through to form an open slot which is wider than a bucket base, the lower end of the slot being of dovetail formation, buckets having bases mounted upon and secured in place by the rib and located on opposite sides of the slot therein, the bases of the buckets adjacent the slot slightly overhanging the cut ends of the rib, and a filling block anchored in the dovetail slot in the rim and exerting a wedging action limited to the bucket bases, 45 the sides of the block being separated from the walls of the cut in the rib by a small clearance. 50

5. A turbine wheel having a rim, an annular rib located on the peripheral surface thereof of dovetail shape in cross-section, the rim and rib being cut through in a plane perpendicular to that of the wheel to form a bucket assembling slot, the portion of the slot in the rim being of dovetail formation, buckets having bases which taper toward the axis of the wheel and engage the rib and are securely held thereby against centrifugal forces, the bases being located on opposite sides of the slot and overhanging the sides thereof, and a filling block for the slot having a dovetail foot at its inner end securely fitted into the slot in the rim and a slightly enlarged head on its outer end which engages the buckets only in regions having a greater diameter than the rib, the sides of the block below the head and between it and the foot being separated from the adjacent cut ends of the rib by a small clearance 55 so that the wedging effect of the block is wholly exerted on the bucket bases outside of the rib. 60
